UNITED STATES PATENT OFFICE.

CLARENCE E. REED AND SAM SORENSEN, OF HOUSTON, TEXAS; SAID SORENSEN
ASSIGNOR TO SAID REED.

WELL-DRILLING TOOL.

1,405,160.

Specification of Letters Patent. Patented Jan. 31, 1922.

Application filed June 15, 1921. Serial No. 477,783.

To all whom it may concern:

Be it known that we, CLARENCE E. REED and SAM SORENSEN, citizens of the United States, and residents of Houston, in the county of Harris and State of Texas, have invented certain new and useful Improvements in Well-Drilling Tools, of which the following is a specification.

Our invention is particularly adapted for 10 operating in what is known as gumbo or sticky shale and similar formations, and the invention consists in the features and combination and arrangement of parts herein- 15 after described and particularly pointed out in the claims.

In the drawings:

Figure 1 is a side elevation of the invention.

Fig. 2 is a bottom plan view, and 20 Fig. 3 is a view of a detail.

In these drawings cutter blades 1 are shown consisting of flat members with a cutting edge 2. These blades incline upwardly and rearwardly. They are arranged 25 in a plane substantially at right angles to the general axis of the drill which is designed to operate by rotating about this axis. The blades are forged in one piece and they 30 radiate from the axial center of the rotary drill. They are supported by arms 3 which are spaced apart and extend outwardly and downwardly from a shank 4 which is screw threaded to be connected with the lower section of the drill stem. The connection 35 between these arms and the cutting blades 1 may be of various forms, but in the particular construction illustrative of my invention, this connection consists of rivets 5 extending through the lower ends of the arm 40 and through the blades. The arms are shouldered at 6 to afford a bearing for the upper edge of the cutting or scraping blade. The arms on their interior are tapered 45 downwardly as shown at 7.

At the center of the structure there is a post 8 extending down from the shank 4 in line with the axis of the cutter or drill. This member has a conduit 9 formed therethrough, which forms a continuation of a 50 conduit 10 in the shank, so that water may be delivered to the interior of the structure for flushing out the material cut or scraped from the wall of the well being drilled or cut. This post 8 at its lower end connects 55 with the central portion of the cutter organ-

ization and in the particular structure shown the post is tapered at its lower end so as to fit into a corresponding socket at the central portion of the cutting blades. The conduit 9 is extended through the central 60 portion of the cutting blades at 11 and there are ports 12 leading from this conduit in different directions and substantially radially, these ports opening out through the sides of the cutting blades so as to deliver the flushing water at a point between 65 the cutting blades and below the upper edges thereof. The central post 8 not only serves as means for conducting the water to the point where the flushing is to take place, but it also serves to resist the upward thrust 70 and support the cutting blades at the center of the head or drill.

In the action of the device, the blades cut or scrape off the material from the bottom 75 wall of a hole and this material slides upwardly along the inclined faces of the blades and then passes into the open space above the blades which space extends from the upper edges of the cutting blades to the shank. 80 The height of the cutting blades is not great so that the cut material has to pass only a short distance before it passes into the space within the structure over the upper edges of the blades. The rotation of the drill will 85 cause the arms 3 to operate on the loosened or cut material and stir the same, thereby securing a thorough mixture of the sticky material with the water which issues from the ports 12 and in this way the material 90 will be made ready for easy removal by flotation and tendency of the material to ball up by accumulating on the faces of the blades will be prevented, this being an objection to the ordinary fish tail type of drill 95 generally used for cutting material of this character.

The central post 8 acts as a support to prevent collapse of the arms under extreme pressures.

We claim:

1. A rotary well drilling tool comprising blades disposed about the axial center of the tool, with an open space above them for the passage inwardly of the cut material 105 and an open frame support for the said blades, at the lower part of which said blades are located, substantially as described.

2. A rotary well drilling tool comprising a shank, arms depending therefrom and 110

spaced apart and cutting blades at the lower ends of said arms, there being a free space between the arms and between the blades in which the cut material will be subjected to 5 the stirring action of the blades and arms, substantially as described.

3. A rotary well drilling tool comprising a frame, radiating cutting blades at the lower part of said frame, said blades having 10 a space between them and also above them within the frame in which space the cut material will be stirred by said frame and blades, substantially as described.

4. A rotary well drilling tool comprising 15 radiating cutters inclining upwardly and extending inwardly towards the axis of said drill, and an open supporting structure carrying said blades at its lower end, the space between and above the said cutters receiving 20 the cut material to be stirred, substantially as described.

5. A rotary well drilling tool comprising 25 blades connected together at the axis of the tool and radiating therefrom, and a carrying frame comprising a shank and arms radiating from said shank and connected at their lower ends with the blades, said arms being spaced apart.

6. A rotary well drilling tool comprising 30 blades radiating from the axis of the tool, a shank, arms spaced apart, extending from the shank and connected with the blades, and a central post extending from the shank to the blades, substantially as described.

35 7. A rotary well drilling tool comprising cutting blades extending from the axial center, a member having a conduit for water extending to the central portion of the blades and ports extending through the blades to 40 direct water from said conduit to points in between the blades, substantially as described.

8. A rotary well drilling tool comprising

radiating cutter blades disposed in a plane at right angles to the axis of the tool, and 45 supporting means for the said blades having spaced apart portions at the lower ends of which the blades are located, substantially as described.

9. A rotary well drilling apparatus comprising cutters disposed in a plane at right angles to the axis of the tool and radiating from said axis, an open frame supporting said blades, and a central post extending down to the said blades and having a conduit 50 to carry water thereto, substantially as described.

10. A rotary well drilling tool comprising 55 blades disposed in a plane at right angles to the axis of the tool and radiating from 60 said axis, said blades being formed in one piece, a central post in connection with the said blades at its lower end and having a conduit for conveying water, and arms spaced apart and carrying the blades at their 65 lower ends.

11. In combination in a rotary drilling tool for wells, blades arranged on edge and inclining upwardly and inwardly, arms spaced apart and carrying said blades at 70 their lower ends and a central member having a water conduit extending between the said arms for flushing the material cut by the blades.

12. In combination in a well drilling tool, 75 cutting blades arranged on edge and disposed in a plane substantially at right angles to the axis of the tool, an open frame carrying the blades at its lower part and means for supplying flushing water substantially 80 axially of the tool, substantially as described.

In testimony whereof we affix our signatures.

CLARENCE E. REED.
SAM SORENSEN.
